(57) **CLAIM**

The ornamental design for a pair of headphone headset covers with guide passthroughs as shown and described.

DESCRIPTION

FIG. 1 is a front perspective view of one headphone headset cover with guide passthrough, of the pair of headphone headset covers with guide passthroughs, shown separately for purposes of illustration, showing the new design;

FIG. 2 is a rear perspective view of the pair of headphone headset covers with guide passthroughs thereof;

FIG. 3 is a front elevational view of the pair of headphone headset covers with guide passthroughs thereof;

FIG. 4 is a rear elevational view of the pair of headphone headset covers with guide passthroughs thereof;

FIG. 5 is a left side elevational view of the pair of headphone headset covers with guide passthroughs thereof;

FIG. 6 is a right side elevational view of the pair of headphone headset covers with guide passthroughs thereof;

FIG. 7 is a bottom plan view of the pair of headphone headset covers with guide passthroughs thereof;

FIG. 8 is a top plan view of the pair of headphone headset covers with guide passthroughs thereof;

FIG. 9 is an alternate front environmental view of the pair of headphone headset covers with guide passthroughs thereof;

FIG. 10 is an alternate rear environmental view of the pair of headphone headset covers with guide passthroughs thereof; and,

FIG. 11 is a perspective environmental view of a pair of headphone headset covers with guide passthroughs thereof, the opposite perspective view is a mirror image.
